UNITED STATES PATENT OFFICE.

ISAAC LEVY, OF OAKLAND, CALIFORNIA.

PLATE-GAGE FOR SEWING-MACHINES.

1,061,090.

Specification of Letters Patent.

Patented May 6, 1913.

Application filed July 26, 1912. Serial No. 711,643.

To all whom it may concern:

Be it known that I, ISAAC LEVY, a citizen of the United States, residing at Oakland, in the county of Alameda and State of California, have invented certain new and useful Improvements in Plate-Gages for Sewing-Machines, of which the following is a specification.

My present invention relates to plate gages for sewing machines to be disposed on the cloth plate thereof, in proximity to the reciprocating needle, to guide the textile for stitching at a predetermined distance from a margin thereof.

15 The principal object of my invention is to provide a gage which includes a plurality of elements having guide faces so mounted that any one guide face may be quickly disposed in operative relation to the stitching path, to guide the textile for obtaining a seam of a predetermined width.

Further objects of my invention are to provide a plurality of elements having guide faces spaced apart from each other and each 25 disposed at a predetermined distance from a point situated on a base, common to all of the said elements, the said base being adapted to be adjustably mounted upon the cloth plate of the sewing machine, whereby 30 the relative position of the guide faces to the stitching path may be altered, but without altering the relative position of one guide face with respect to the others.

In the drawings, forming a part of this 35 specification:—Figure 1 is a fragmentary plan view of a cloth plate of a sewing machine, showing the application of my invention thereto. Fig. 2 is a vertical sectional view through a portion of the cloth plate, 40 the device embodying my invention being shown in front elevation. Fig. 3 is a sectional view on the lines 3—3 of Fig. 1. Fig. 4 is a sectional view on the lines 4—4 of Fig. 1, taken through one of the guide elements.

Similar characters refer to similar parts throughout the views.

The usual cloth plate is designated by 5, having the needle aperture 6 therein; and 50 a feed bar, by 7, which works in an aperture 8 in said plate 5, to advance the textile. The feed bar 7 is of any suitable design, and the stitching path, which passes through aperture 6, parallel to the longitudinal axis 55 of such bar, is indicated by the line α — α .

The cloth plate 5 is provided with the

usual screw threaded aperture 9 disposed to one side of the stitching path, to receive thumb screw 10, whereby various attachments may be used in operative relation to 60 the stitching mechanism.

The guide elements, as hereinafter described, are mounted upon an elongated base plate 11, having at one end a guide face 12, preferably formed by an upturned portion 65 of the plate, and at its other end, preferably an enlargement or offset portion 13 for a purpose to be subsequently described. An elongated guide slot 14 is provided in plate 11, disposed with its axis preferably at a 70 right angle to the plane of guide face 12, this slot to receive the shank of thumb screw 10, whereby the base plate may be rigidly secured to the cloth plate in an adjusted position. When so mounted, the guide face 12 75 is disposed parallel to the stitching path α — α , at a predetermined distance therefrom to guide the textile for obtaining a seam of the desired width.

The several guide elements, designated 80 generally by 15, carried by the plate 11, are each provided with a stem 16 and a guide face 17 disposed adjacent one end thereof. The elements 15 are each pivoted at a common axis upon the plate 11, as by the pin 85 18, rigidly carried by said plate, and are normally disposed in juxtaposed relation with each other to occupy a space of minimum magnitude.

An essential feature in a device of this 90 character is that the guide face 17 contacts with the cloth plate 5 in order to effectively guide the cloth, and also, the said guide face must be of sufficient height above the plane of said cloth plate to guide cloth of 95 considerable thickness. In order to provide for the desired compactness of the device without detracting from its ability to serve effectively as stated, the guide faces are disposed to lie in spaced apart stepped relation to each other, as clearly shown in Fig. 2 of the drawing, when the several elements are in juxtaposed relation to each other. Thus, the faces 17 are positioned at a predetermined distance from the axis of pin 100 18, which positioning enables the device to be used in obtaining seams of different widths.

Any one of the elements 15 may be swung about the axis of pin 18 exposing the guide 110 face 17 of the next adjacent element to serve as a guide relative to the stitching path

x—x, the said faces, when the device is in a compact condition, lying in planes parallel to each other and parallel to the guide face 12.

5 I prefer to carry the guide faces 17 of each element 15 by an angular extension 19, extending from stem 16 and disposed to present the said faces 17 in front of the said face 12, when the device is in a compact 10 form, so that all of the guide faces have the same relative transverse disposition with respect to the stitching path *x—x*. I also prefer to mount pin 18 upon the said offset portion 13 of plate 11, so that the stem 16 of 15 elements 15 may extend to one side of plate 11 and abut against an abutment 20 carried by such plate, which limits oscillation of the members 15, in one direction, to position the 20 guide faces 17 thereof in parallelism with the stitching path *x—x*.

The operation of the device is as follows:—The plate 11 having been secured to plate 5, by the thumb screw 10, with the guide face 12 at a predetermined position 25 from and parallel to the stitching path *x—x*, this face 12 may serve to guide the cloth to provide a seam of maximum width, all of the elements 15 having been swung out of operative relation to said path *x—x*. To 30 obtain a seam of less width than may be obtained by the guidance of face 12, the element 15, which, upon being swung into operative relation with the path *x—x*, positions its guide face at a distance from said line, 35 equal to the desired positioning of the stitching of the textile, is then used. For instance, in Fig. 1, the top three elements 15 are shown as swung out of operative relation to the stitching path, and the fourth 40 element from the top may serve as the guide.

Changes in detail may be made without departing from the spirit and scope of my invention; but,

I claim:—

45 1. A gage of the character described comprising in combination, a base plate having an elongated slot, a plurality of juxtaposed elements having guide faces, and means pivoting said elements to said plate with an 50 axis of oscillation common to all of the said elements, the said guide faces of said elements being positioned at different distances from said axis, and at a right angle to the axis of said slot in said plate, and adapted to 55 lie in planes parallel to each other, or to be swung out of such position, about the said axis of oscillation.

60 2. A gage of the character described comprising in combination, a base plate, a plurality of juxtaposed elements having guide faces, and means pivoting said elements with

an axis of oscillation common to all of the said elements, said guide faces of said elements being positioned at different distances from the said axis and adapted to lie in 65 planes parallel to each other, or to be swung out of such position, about the said axis of oscillation.

3. A gage of the character described comprising in combination, a base plate, a plurality of juxtaposed elements having guide faces, means pivoting said elements to said base plate with an axis of oscillation common to all of the said elements, said guide faces of said elements being positioned at different distances from the said axis and adapted to lie in planes parallel to each other, or to be 70 swung out of such positions, about the said axis of oscillation, and means carried by said base plate for limiting oscillation of said 75 elements in one direction, to position the said guide faces thereof in parallelism, substantially as and for the purpose set forth.

4. A gage of the character described comprising in combination, a base plate provided 85 with a guide face and having an elongated slot with its axis disposed at right angles to the plane of said base, a plurality of juxtaposed elements having guide faces, and means pivoting said elements to said plate 90 with an axis of oscillation common to all of the said elements, the said guide faces of each element being positioned at different distances from the said axis and adapted to lie in planes parallel to the plane of the 95 said guide face of the base plate, or to be swung out of such position about the said axis of oscillation.

5. A gage of the character described comprising in combination, a base plate, a plurality of elements including a stem portion, an angular extension at one end thereof and a guide face carried by said extension, means pivoting said elements to said base plate, at their ends opposite from said guide face, 105 and in juxtaposed relation with each other with the said stem portion to one side of said base plate and with said faces positioned in planes parallel to each other, said stems being adapted to be swung about said pivot 110 out of said position, and an abutment carried by said base plate to engage with said stem portions of said elements to limit movement thereof in one direction, to position the said guide faces thereof in parallelism, substantially 115 as and for the purposes set forth.

In testimony whereof I affix my signature in presence of two witnesses.

ISAAC LEVY.
